Primary Examiner — Darlington Ly

(57) **CLAIM**

The ornamental design for a current transducer, as shown and described.

DESCRIPTION

1. Current transducer

1.1 is a top perspective view of a current transducer showing my new design;

1.2 is a bottom perspective view thereof;

1.3 is a front elevation view thereof;

1.4 is a rear elevation view thereof;

1.5 is a top plan view thereof;

1.6 is a bottom plan view thereof;

1.7 is a left side elevation view thereof; and

1.8 is a right side elevation view thereof.

The broken lines in the reproductions illustrate portions of the current transducer that form no part of the claimed design.
